BORE SIGHT FOR INSERTION IN THE
BREECH CHAMBER OF GUNS TO PRO-
VIDE OVERLAPPING IMAGES OF MU-
ZZLE PORTIONS OF THE GUN BORES

Leo H. Brown, Glenville, Conn.

Application May 23, 1944, Serial No. 536,933

5 Claims. (Cl. 88—1)

(Granted under the act of March 3, 1883, as
amended April 30, 1928; 370 O. G. 757)

1

The invention described herein may be manufactured and used by or for the Government for governmental purposes without the payment to me of any royalty thereon.

The present invention relates to a bore sight for guns or cannon.

A bore sight is used to determine whether the line of sight of an external sighting device of a gun or cannon is parallel with the axis of the bore of a gun or cannon. A bore sight is also used in adjusting the line of sight of an external sighting device of a gun or cannon into parallelism with the axis of the bore of the gun or cannon. Thus, for example, where a telescopic sight or a collimator sight or a reflex sight is used as the external sighting means for cannon, a bore sight is used to determine whether the line of sight of the telescope, collimator sight or reflex sight is adjusted parallel to the axis of the bore of the cannon.

Heretofore in determining whether this parallelism existed or in establishing it, two lengths of cord or thread were stretched, at right angles to each other, coincident with diameters across the bore at the muzzle end of the cannon or gun, and a disk which exactly fitted the chamber of the cannon or gun, and having a small hole therethrough at its center, was inserted within the chamber of the gun or cannon through its breech. The line or line of sight between the intersection of the two lengths of cord and the small hole through the disk substantially coincides with the axis of the bore of the cannon. With the breech end of the gun open, one sighted through the bore on a distant target, placing the center of the opening in the disk and the intersection of the cords in line with the target or a selected portion thereof. Then the external sighting device of the cannon or gun, such as a telescopic sight, or a collimator sight, was sighted on the same target or on the same portion or point of the target. This placed the line of sight of the external sighting device substantially parallel with the axis of the bore of the gun.

One of the main objections to the above mentioned procedure of bore sighting is that the cords must be stretched across the muzzle end of the bore. Where for example, a cannon is mounted on a combat tank, this placing of the cords across the bore of the cannon at the muzzle end is only an inconvenient procedure, requiring personnel manning the tank to leave their posts within the tank and to mount upon the exterior of the tank to place the cords in position, but also the pro-

2

cedure is a hazardous one during combat or within the field of operations.

Considering the rough terrain over which combat tanks are required to travel, it will readily be appreciated that the gun sights are very much subject to being jarred out of adjustment, and the necessity of bore sighting may be frequent.

It will, therefore, be understood that it is of importance to be able, easily and effectively, to 10 place the line of sight of the sighting means for cannon mounted on a combat tank into parallelism with the axis of the bore of the cannon, or to determine whether such parallelism exists, without it becoming necessary for personnel 15 manning the tank to leave their posts in the interior of the tank. One of the objects of the present invention is to provide apparatus, or a bore sight, which enables this to be done. Another object of the invention is to provide apparatus of 20 the character referred to which is easy or simple to use, and which in addition is of simple construction and rugged.

The bore sight of the present invention includes means for sighting, from the breech end 25 of a gun or cannon along the surface of the bore, along a line parallel with the axis of the bore, to obtain a view of at least a part of the periphery of the muzzle end of the bore; also another means, which is spaced circumferentially of the bore 30 from the sighting means previously referred to, for also sighting, from the breech end of the cannon, along the surface of the bore, along another line parallel with the axis of the bore, so as to obtain another view of at least a part of the 35 periphery of the muzzle end of the bore, and means for overlapping the two views so obtained.

When the above mentioned views are overlapped, the circular peripheries, or the portions of the circular peripheries, of the muzzle end of the 40 bore of the cannon intersect, and their point or points of intersection establishes a line of sight, through the bore, parallel to the axis of the bore. The barrel of the gun or cannon is now moved in azimuth and in a vertical plane so as to place the 45 said intersection in the overlapped views on a selected distant target or on some particular point thereon. The external sight of the cannon is now adjusted so that its line of sight is on the same target or on the same selected point thereof. 50 After this adjustment has been made, the line of sight of the external sight is parallel with the axis of the bore of the cannon or gun.

The drawings accompanying this description, and forming part thereof, illustrate one embodiment of the invention. In these drawings where-

in the same reference character indicates the same or similar parts.

Fig. 1 is a longitudinal section of a part of a cannon barrel along a plane parallel with but removed from the axis of the bore of the cannon, and showing, partly in section and in plan, a bore sight according to the invention placed in position in the chamber of the cannon for use in bore sighting.

Fig. 2 is a rear elevation of the bore sight shown in Fig. 1.

Fig. 3 is a side elevation of the bore sight shown in Fig. 2.

Fig. 4 is a section on the line 4—4 of Fig. 2.

Figs. 5, 6 and 7 are typical examples of two overlapped views referred to above, and indicate fields of view as seen by a person using the sight.

Referring now in detail to the drawings, the numeral 1 indicates the barrel of a cannon, having the bore 2 and the chamber 3.

The bore sight comprises a frame or disk 5 which accurately fits with a sliding fit against the periphery of the chamber 3. The chamber 3 may taper slightly towards the muzzle, so that the disk 5 may reach a position in the chamber such that further movement towards the muzzle is not possible. This is not disadvantageous because, it is preferable to insert the disk 5 only a short distance in the chamber 3.

Over a chord of the disk 5 is secured a housing 6 containing prisms 7 and 8. Prisms 7 and 8 may be of glass or other light transmitting material and are of the same index of refraction. Prism 7 is cemented to prism 8 by a transparent cement having the same or about the same index of refraction as prisms 7 and 8. Before prisms 7 and 8 are cemented together, one of the faces of them forming the interface 9 is provided with a half-silvered mirror, that is to say, a mirror that reflects about 50% of light incident thereon and transmits 50% of the said incident light. Said mirror surface, instead of being formed of silver, may be formed of any other suitable substance providing a coating which partially reflects light and partially transmits light. There is, therefore, in the interface 9 between the prisms 7 and 8 a mirror or reflector which partially reflects and partially transmits light.

The interface 9 and the face 10 of the prism 8 are parallel and each of them is at an angle of 45° with the said chord of the disk, as clearly shown in Fig. 4 of the drawing. The longitudinal axis of the prism 8 is parallel with the chord.

The prisms 7 and 8 closely fit within the housing and against the disk 5, so that when the housing 6 is secured to the disk 5 by means of the screws 11, the said prisms will be held securely in the position shown in Fig. 4.

Two small openings 14 and 15 passing entirely through the disk 5 are provided near each end of the said chord of the disk, and these openings are so positioned that the axis of opening 14 produced intersects the interface 9 about at its middle, and the axis of the opening 15 produced intersects the total reflecting surface 10 of the prism 8 at about its middle point.

The centers of the openings 14 and 15 are so located on the above mentioned chord of the disk 5 that the axes of the holes 14 and 15 when projected into the bore 2 of the cannon barrel are parallel with the axis of the bore, and substantially coincident with the surface of the bore.

Thus, the opening 15 and the reflector or reflecting surface 10 are so disposed that light pass-

ing down the bore of the cannon parallel to that part of the surface of the bore adjacent the opening 15, and also parallel to the axis of the bore, is reflected at right angles to its path, whereby it is directed upon the partially light reflecting and light transmitting mirror or reflector in the interface 9. This light is then again reflected at right angles by the mirror in the interface 9 and proceeds out of the housing 6 through the opening 17 to the eye of the person using the instrument. Also, it will be observed that light passing down the bore parallel to that part of the surface adjacent the opening 14, and also parallel to the axis of the bore, will pass through opening 14 into prism 7, and then through interface 9 and opening 17 in housing 6 to the eye of the person using the instrument. The mirror in the interface 9 overlaps the view of the periphery of the muzzle end of the bore 2 obtained through the opening 15 upon the view obtained through the opening 14. Figs. 5, 6 and 7 illustrate examples of such overlapped views.

In Figs. 5 and 6 arcs 20 and 21 indicate the views of the periphery of the muzzle end of the bore obtained through openings 14 and 15 respectively, and their intersection is indicated by the numeral 22.

In Fig. 7, the circles 23 and 24 indicate the views of the entire periphery of the muzzle end of the bore obtained through openings 14 and 15 when the eye is relatively close to the opening 17 in the housing 6. The point of intersection 25 of these two circles corresponds to the point of intersection 22 in Figs. 5 and 6.

Openings 26, within which the thumb and two fingers of one hand may be inserted, are provided in the disk 5 to facilitate its insertion in and removal from the chamber 3 of the cannon. Small opening 27 is provided at the exact center of the disk 5 when it is desired to bore sight when using intersecting cords or threads across the muzzle end of the bore, according to the known method of bore sighting described above.

In use, the bore sight is inserted in the cannon as shown in Fig. 1. Then the eye of the observer or user is placed in line with the opening 17 of the housing 6. The cannon barrel is then moved in azimuth and in a vertical plane until a point of intersection 22 or 25 is on a distant target or on some particular point thereof, as for example on the top of the telegraph pole shown in Fig. 5. Now the external sight, for example a telescopic sight or a collimator sight, is sighted on the same target or point, and when this is accomplished the line of sight of the external sight and the axis of the bore of the cannon are substantially parallel. The observer sees two overlapping images through the bore sight whose centers are displaced a distance equal to the distance between the two parallel mirrors 9 and 10, that is, the distance between the centers of holes 14 and 15. As an example, in a gun with bore diameter of three inches the displacement of the intersections of the rim portions would be about two inches.

Thus, the double image of the front of the bore would appear as in Fig. 7, when the eye is positioned very close to the aperture 17. However, a displacement of two inches at the distant target will subtend a negligible angle at the gun and one which cannot be detected with the naked eye. With the eye at a greater distance from aperture 17, two images (each defined by a respective arc 20 and 21) of distant objects would overlap so as to have an area in common, thus giving an appearance similar to Fig. 5. It follows that either

of the apparent intersections shown in Figure 7 can be used for bore sighting, with equally accurate results.

In the appended claims, the term "gun" is used in a broad sense as including cannon, mortars, howitzers, and all caliber ordnance for projecting missiles or projectiles in connection with which the invention can be usefully employed for the purposes described. The term "element" as used in the claims in connection with the gun bore, means any line lying in the surface of said bore and formed by the intersection therewith of a plane passing through the central longitudinal axis of said bore.

I claim:

1. A bore sighting device comprising a disc adapted to fit within the breech portion of a gun transversely across the longitudinal axis of the bore of said gun, there being spaced sighting apertures in said disc, each adapted when said disc is in said breech portion, as aforesaid to define a line of sight parallel to said axis and closely adjacent a respective element of the surface of said bore, an optical prism carried by said disc having parallel end faces extending at 45° across the respective lines of sight, one of said faces being partially reflecting and the other of said faces being totally reflecting, and a supplemental prism secured to said partially reflecting face, whereby overlapping views of spaced portions of said bore surface at the muzzle of a gun may be afforded at an observing position at the breech thereof.

2. A bore sight comprising a member adapted to fit within and against the walls of the breech chamber of a gun in a plane normal to the axis of the bore of said gun, a reflector carried by said member so as to lie upon a chord of the cross section of said chamber adjacent said member, in position to reflect at right angles, along said chord, an image of a first portion of the muzzle end of the bore of said gun, a partial reflector element carried by said member in position to deflect said image rearwardly parallel to the bore axis while simultaneously transmitting parallel with said bore a direct view of a second portion of the muzzle end of the bore of said gun, whereby overlapping views of said portions may be simultaneously observed at a position rearwardly of said member.

3. In a bore sighting device for guns, disc means adapted to be positioned within the breech portion of the bore of a gun in predetermined transverse relation to the axis of said bore, said disc having means which, when said disc is so positioned, defines spaced lines of sight each parallel to said axis and closely adjacent a respective ele-

ment of the surface of said bore, and optical prism means carried by said disc means and adapted to project along one said line of sight overlapping images of muzzle portions of said bore adjacent the respective elements and to project said overlapping images to an observing position at the breech of said gun.

4. A bore sight comprising a disc adapted to fit within the breech chamber of a gun transversely across the bore axis of said gun, said disk having first and second openings adjacent the periphery thereof whose centers determine a chord of a cross section of the bore of said gun, a first reflector carried by said disk over the first said opening and positioned to reflect at right angles parallel to said chord an image of a first portion of the muzzle of the gun, a partial reflector carried by said disk over said second opening and positioned to reflect said image rearwardly along a line parallel to the axis of the bore of said gun and an optical element cooperating with said partial reflector to transmit rearwardly an image of a second portion of the muzzle of said gun adjacent said line, whereby overlapping images of said portions may be simultaneously observed.

5. In an instrument for bore sighting a gun, a frame adapted to be positioned across the breech portion of the bore of said gun in fixed relation with said gun, means carried by said frame and defining, when said frame is positioned as aforesaid, first and second spaced parallel sight lines each closely adjacent the surface of said bore and parallel with the axis thereof, first means comprising an optical prism carried by said frame to project to a viewing position at the breech of the gun, a first view of the muzzle portion of the gun bore adjacent said first line, and second means carried by said frame and comprising an optical prism cooperating with said first prism to project into overlapping relation with said first view at said position, a second view of the muzzle portion of said gun proceeding along said second line, said overlapping views including an image of intersecting rim sections of said muzzle portions to thereby provide a sighting point.
